(57) **CLAIM**

The ornamental design for a luminaire, as shown and described.

DESCRIPTION

FIG. 1 is a perspective view of a luminaire, showing my new design;

FIG. 2 is a front side elevation view thereof;

FIG. 3 is a right side elevation view thereof;

FIG. 4 is a back side elevation view thereof;

FIG. 5 is a left side elevation view thereof;

FIG. 6 is a top plan view thereof; and

FIG. 7 is a bottom plan view thereof;

FIG. 8 is a perspective view of an alternate embodiment of a luminaire, showing my new design;

FIG. 9 is a front side elevation view thereof;

FIG. 10 is a right side elevation view thereof;

FIG. 11 is a back side elevation view thereof;

FIG. 12 is a left side elevation view thereof;

FIG. 13 is a top plan view thereof; and,

FIG. 14 is a bottom plan view thereof.

The broken line disclosure represents portions of the luminaire which form no part of the claimed design, and no claim is made to the area between the dash-dot-dot-dash broken away lines.
